UNITED STATES PATENT OFFICE.

PETER J. FERGUSON, OF ANETA, NORTH DAKOTA.

DRENCHING DEVICE.

1,182,002.

Specification of Letters Patent.

Patented May 9, 1916.

Application filed May 29, 1915. Serial No. 31,223.

To all whom it may concern:

Be it known that I, PETER J. FERGUSON, a citizen of the United States, residing at Aneta, in the county of Nelson and State of North Dakota, have invented certain new and useful Improvements in Drenching Devices, of which the following is a specification.

My present invention relates to an improved drenching device designed primarily to facilitate the administering of medicine to horses and other live stock and to this end, the device includes an improved yoke structure which is to be supported on the neck, a crupper strap to engage the stock of the tail and hold the yoke in an upright position, and means coöperating with the yoke to forcibly spread the jaws of the animal.

Various other objects and advantages will become apparent during the continuance of the following description.

The above and other objects which will become apparent, are accomplished by such means as are shown in their preferred form in the accompanying drawings, described in the following specification and then more specifically pointed out in the appended claims.

In the accompanying drawings wherein like characters designate like parts throughout the several views; Figure 1 is a perspective view of my invention showing the same as in an operative position. Fig. 2 is a perspective view of the improved yoke structure which is employed. Fig. 3 is a detail view of the crupper strap. Fig. 4 is a plan view of a neck band strap which is employed. Fig. 5 is a sectional view showing the means for securing the yoke structure to the neck band strap. Fig. 6 is a detail view illustrating a portion of the flexible element employed to spread the jaws of the animal.

My invention consists generally of a comparatively wide neck band strap 10 which carries at its respective extremities suitable fastening elements as indicated by the numerals 11 and 12. The strap 10, in the use of my invention, is designed to fit snugly about the neck of the animal substantially in the position shown in Fig. 1 and is adapted to support the yoke structure which will hereinafter be described at length. In order to more securely support the yoke structure the neck band strap is provided at suitable points with outstanding pins 13 upon which

may operate the securing elements 14 and if so desired suitable washers such as indicated at 15 may be used in conjunction therewith.

The improved yoke structure which is employed consists of a substantially horizontal body member 16 which carries the substantially parallel standards 17. The standards 17 are provided at a point adjacent their lower end with openings 18 for the purpose of receiving the pins 13 which are carried by the neck band strap. After the pins 13 have been positioned in place in conjunction with the yoke structure, the retaining elements 14 and the washers 15 may be utilized for the purpose of attaining a tight connection.

The body member 16 of the yoke structure revolvably supports a guiding roller 19 through the medium of spaced apart brackets 20 in order to accommodate a flexible operating member 21. A strap bracket is also carried upon the body member 16 in proximity to the guiding roller 20 and serves the purpose presently described.

As shown in Fig. 1, a crupper strap 23 is provided, one end of which is designed to embrace the stock of the tail of the animal while its other end is adjustably connected to the strap bracket 22 of the yoke structure. The adjustment of the crupper strap may be attained through the medium of the buckle 24 which coöperates with the adjustable strap element 25. The function performed by the crupper strap in this instance is readily apparent. When in place, it prevents the forward oscillation of the yoke structure during the drenching operation and retains the same in a substantially upright position.

One end of the flexible element 21 is formed into a loop as at 26, and in the use of the device, the same is arranged about the upper jaw of the animal as shown in Fig. 1. The operator exerts a pulling stress upon the free end of the element 21 which will cause the guiding roller 19 to rotate and allow the flexible element to elevate the head of the animal and by so doing to forcibly spread its jaws. This operation is clearly illustrated in Fig. 1. When the head of the animal is in an elevated position such as illustrated medicine can be easily administered or if it is desired, the mouth and throat of the animal can be thoroughly examined.

From the foregoing it is believed that the

novel features of my invention will be apparent and in view of the exceedingly simple construction thereof, it is believed that the same may be manufactured at a comparatively low cost.

In reducing my invention to practice I find that the form referred to herein as the most practical and preferred embodiment is the most efficient, but realizing that certain 10 conditions will necessarily vary in concurrence with the adoption of my device, I desire to emphasize the fact that various minor changes in the details of construction and in the proportion of parts may be resorted to 15 when required without sacrificing any of the advantages of my invention as defined in the appended claims.

Having thus fully described my invention, what I claim as new and desire to secure 20 by Letters Patent is:

1. In a device as set forth, an upright, means for supporting said upright from the animal and a flexible member movably carried by said upright and adapted to engage 25 in the mouth of the animal.

2. In a device as set forth, a neck band strap, a yoke attached at its end thereto, a crupper strap carried by said yoke and a flexible member movably attached to said 30 yoke, substantially as described.

3. In a device as set forth, a neck band strap, a yoke pivotally attached at its end to said strap, a crupper strap attached to said yoke; a roller revolvably supported on 35 said yoke, and a flexible member operating on said roller, one end of said flexible member being looped.

4. In a device as set forth, a neck band strap, a yoke pivotally attached at its end 40 to said strap, a crupper strap, a bracket on said yoke, means connecting said crupper strap and said bracket, a roller revolvably supported on said yoke, a flexible member operating on said roller, and one end of 45 said flexible member being looped.

Copies of this patent may be obtained for five cents each, by addressing the "Commissioner of Patents, Washington, D. C."

5. In a device as set forth, a comparatively wide neck band strap, outstanding pins carried by said strap, said pins being screw threaded a portion of their length, a yoke, said yoke including vertical standards, said standards being provided with openings adjacent their lower ends for the reception of said pins, means coöperating with said pins to retain said standards in position, a crupper strap having connection 55 with said yoke and a flexible operating member operating on said yoke, as and for the purpose specified.

6. In a device as set forth, a comparatively wide neck band strap carrying fastening means at the respective ends thereof, outwardly projecting pins carried by said neck band strap and screw threaded a portion of their length, a yoke including vertical standard portions, said standards being provided with openings adjacent their lower ends for the reception of said pins, means coöperating with said pins for retaining said standard portions thereon, a crupper strap, a bracket on said yoke having connection with said crupper strap, a roller revolvably mounted on said yoke, and a flexible member trained over said roller, one end of said operating member being looped.

7. In a device as set forth, a neck band strap, a yoke attached at its ends thereto, means to resist movement of said yoke in one direction and a flexible element movably carried by said yoke and adapted to engage in the mouth of the animal to resist movement of said yoke in an opposite direction.

In testimony whereof I affix my signature in presence of two witnesses.

PETER J. FERGUSON.
